UNITED STATES PATENT OFFICE.

FRANK W. EDWARDS, OF LOGANSPORT, INDIANA, ASSIGNOR TO THE CHICAGO LUBRICATOR COMPANY, OF CHICAGO, ILLINOIS, A CORPORATION OF ILLINOIS.

AUXILIARY OIL-CUP FOR SIGHT-FEED LUBRICATORS.

No. 839,878.

Specification of Letters Patent.

Patented Dec. 25, 1906.

Application filed June 16, 1906. Serial No. 322,100.

To all whom it may concern:

Be it known that I, FRANK W. EDWARDS, a citizen of the United States, residing at Logansport, in the county of Cass and State of Indiana, have invented a certain new and useful Improvement in Auxiliary Oil-Cups for Sight-Feed Lubricators, of which the following is a full, clear, and exact description.

In the use of condensation-displacement sight-feed lubricators it is sometimes necessary to replace or supplement the feed of oil from the oil-bowl to one or more of the sight-feeds by an auxiliary oil-cup, and it is a common practice to construct such lubricators with facilities for introducing these auxiliary oil-cups.

The present invention is concerned with this sort of apparatus; and the object of the invention is to provide an auxiliary device that may be applied to the upper feed-arm of the lubricator, so that the auxiliary supply of oil can be delivered to the upper feed-arm and into the oil-pipe without shutting off the lubricator steam or engine throttle.

In the accompanying drawings, illustrating the invention, in the several figures of which like parts are similarly designated, Figure 1 is an elevation of a locomotive-lubricator of the class described having two auxiliary oil-cups applied to its cylinder-heads. Fig. 2 is a cross-section, partly in end elevation and on a larger scale, of a portion of the lubricator of Fig. 1. Fig. 3 is a cross-section of a modification.

The oil-bowl 1, condenser 2, circulating-pipes 3, water-valve 4, pipe-plug 5, pressure-valve 6, steam chest or cylinder sight-feeds 7, air-pump sight-feed 8, observation glass or index 9, oil-bowl drain-valve 10, filler-plug 11, and other parts shown, but not particularly described, may be of usual or approved construction and are here shown as of the construction known on the market as "the Chicago locomotive-lubricator, Class C;" but it is to be understood that the present invention is not limited to its use with that form of lubricator alone.

As shown, the auxiliary oil-cups 12 are provided with nipples 13, screwed into the nipples of the upper feed-arms 14 of the steam chest or cylinder sight-feeds. Since these oil-cups are alike, a description of one will suffice for both. The oil-cup, preferably,

is cylindrical, with a saucer-shaped top 15, having a filling-hole 16 made as a valve-seat. 55 The filling-plug 17 is adapted to be seated in the filling-hole and has a screw-threaded extension 18 screwing into a hollow boss 19, rising from the bottom 20. This extension has a lateral hole 21 above the boss and intersecting a longitudinal hole 22, opening at the bottom of the extension and within the boss. The boss is pierced transversely at the bottom and in line with the nipple 13 and the opposite nipple 23. This nipple 23 supports 65 the oil-cup feed-valve 24, which has screw-threaded engagement therewith and extends through the opening in the boss, and its point is coned to serve as a valve in a seat 25 in the nipple 13. The oil-cup has a drain-valve 26 70 in its bottom, which drain-valve is made as a screw-plug having a longitudinal bore 27, intersected by a lateral bore 28. The upper feed-arm 14 has the pressure-controlling valve 29 seating in the top of the sight-feed, 75 and the same fitting has a tallow-pipe connection 30.

Instead of the filler-plug 17, screwed into the boss, rising from the bottom of the oil-cup I may use an oil-cup 31, Fig. 3, having a 80 screw-threaded hole 32, in which is screwed the flat valve 33. One side of the oil-cup is made with a channel 34, opening at its top at 35 into the oil-cup and having an opening in its bottom for the reception of the plug or 85 valve 24. Both forms of oil-cups operate in substantially the same way—that is to say, the oil contained therein is displaced by steam-pressure—in one case through the channel formed by the bore 21 22 and in the 90 other case by the channel 34 35. The water of condensation overflows through connection 30.

In order to fill the cup, it is first drained thoroughly by opening the drain-plug 26. 95 Before the drain-plug is opened, however, the valves 24 and 29 are closed, and the filler-plug is opened sufficiently to vent the cup. After the cup is drained the valves are closed and the filler-plug is opened wide, and then the oil is poured into the cup through the filler-plug, and after the oil-cup is filled then the filler-plug is screwed down tight to its seat and feed-valve 29 is opened wide, permitting the pressure from the upper feed-arm to pass into the bottom of the oil-cup 105

and effect the movement or feeding of the oil. Each of the channels shown by parts 21 22 or 34 35 constitutes a sort of circulating-passage, which prevents the oil from stagnating in the 5 top of the cup.

What I claim is—

1. In a sight-feed lubricator, an oil-bowl, a sight-feed adapted to be supplied with oil from the oil-bowl and having an upper feed-arm provided with a pressure-controlling-valve, in combination with an auxiliary oil-cup applied in the upper feed-arm and in communication with the pressure-controlling valve, and having itself an independent pressure-controlling valve, and an oil-circulating channel.
2. An auxiliary oil-cup having means for directly applying it in the upper feed-arm of a sight-feed lubricator, and also having a top filling-plug, a pressure-controlling valve arranged in its bottom, and an oil-circulating channel controlled by said valve.
3. An auxiliary oil-cup for sight-feed lubricators, having a filling-plug in its top, a

boss into which said filling-plug screws, an 25 oil-circulating channel in said plug, means to connect the oil-cup with the upper feed-arm of a sight-feed, and an independent pressure-controlling valve arranged in the oil-cup and controlling the admission of pressure into the 30 oil-cup and the discharge of the oil therefrom.

4. An auxiliary oil-cup for sight-feed lubricators, having a filling-plug in its top, a boss into which said filling-plug screws, an 35 oil-circulating channel in said plug, means to connect the oil-cup with the upper feed-arm of a sight-feed, an independent pressure-controlling valve arranged in the oil-cup and controlling the admission of pressure into the 40 oil-cup and discharge of the oil therefrom, and an oil-cup drain-plug.

In testimony whereof I have hereunto set my hand this 16th day of June, A. D. 1906.

FRANK W. EDWARDS.
